United States Patent Office.

IMPROVED SPRING-HOLDER FOR BED-BOTTOMS.

RUFUS LAPHAM, OF NEW YORK.

Letters Patent No. 59,799, dated November 20, 1866.

SPECIFICATION.

TO WHOM IT MAY CONCERN:

Be it known that I, RUFUS LAPHAM, of the city, county, and State of New York, have made certain improvements in Springs for Beds and other purposes, and I do hereby declare that the following is an exact description thereof, reference being had to the accompanying drawings and to the letters of reference marked thereon:

The nature of my invention consists in attaching a spiral spring to a malleable casting as a base, having a screw thereon, so as to be easily attached as desired.

To enable others skilled in the art to make and use my invention, I will proceed to describe its construction and operation.

Figure 1 represents sections of a bedstead rail and slat, with the spring attached.

Figure 2 represents the casting, with a section of the spring and pin.

Figure 3, the malleable casting, which is made with a seat of the same inclination of the spring, S, to be attached, outside of which are points projecting upward as represented by p, p, p, p, to be bent over the lower round of the spring so as to hold it to its seat firmly. Instead of these points a thin shell around may answer which can be bent over instead of the points. This base or seat is left open in the centre to correspond to the inner size of the spring, so as to allow a pin, P, to pass to guide and govern the slat, as seen in fig. 1. This base or seat has a screw, S', by which it is attached to the rail, R, or work, very readily.

The utility of my invention is easily seen, especially when applied to beds already in use, as nothing is to be taken to produce a perfect spring for a bed except the small casting spring and pin, in the majority of cases. It is also very simple, elastic, and durable.

What I claim, and desire to secure by Letters Patent, is—

1. The device for attaching the spring to its seat, substantially as described.
2. The combination of the screw, seat, and spring, substantially as described.
3. Also the combination of the seat, spring, and pin, as substantially described.

RUFUS LAPHAM.
